The ornamental design for a portable and expandable protected garden building, as shown and described.

DESCRIPTION

FIG. 1 is a front, right side, top perspective view of a first embodiment of the portable and expandable protected garden building showing my new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top plan collapsed view thereof;

FIG. 9 is a front, right side, top perspective view of a second embodiment of the portable and expandable protected garden building;

FIG. 10 is a front side elevational view thereof;

FIG. 11 is a rear side elevational view thereof;

FIG. 12 is a right side elevational view thereof;

FIG. 13 is a left side elevational view thereof;

FIG. 14 is a top plan view thereof;

FIG. 15 is a bottom plan view thereof; and,

FIG. 16 is a top plan collapsed view thereof.

In FIGS. 2-5, 8, 10-13, and 16, the diagonal breakaway lines at the edge of the grid pattern indicate that the grid pattern extends throughout the remainder of the surface, but is not shown for convenience of illustration.
